(57) **CLAIM**

The ornamental design for the belt or pant retentive shaped bottle holder.

DESCRIPTION

FIG. 1 is a perspective view of the belt or pant retentive shaped bottle holder showing my new design, incorporating a bottle shaped base;

FIG. 2 is a front view thereof;
FIG. 3 is a rear view thereof;
FIG. 4 is a top plan view thereof;
FIG. 5 is a bottom plan view thereof;
FIG. 6 is a side view, with the opposite side view being a mirror image thereof;
FIG. 7 is a perspective view of a second embodiment, for a shorter bottle;
FIG. 8 is a front view thereof;
FIG. 9 is a rear view thereof;
FIG. 10 is a top plan view thereof;
FIG. 11 is a bottom plan view thereof;
FIG. 12 is a side view, with the opposite side being a mirror image thereof;
FIG. 13 is a perspective view of a third embodiment;
FIG. 14 is a front view thereof;
FIG. 15 is a rear view thereof;
FIG. 16 is a top plan view thereof;
FIG. 17 is a bottom plan view thereof;
FIG. 18 is a side view, with the opposite side view being a mirror image thereof;
FIG. 19 is a perspective view of a fourth embodiment;
FIG. 20 is a front view thereof;
FIG. 21 is a rear view thereof;
FIG. 22 is a top plan view thereof;
FIG. 23 is a bottom plan view thereof;
FIG. 24 is a side view, with the opposite side view being a mirror image thereof;
FIG. 25 is a perspective view of a fifth embodiment;
FIG. 26 is a front view thereof;
FIG. 27 is a rear view thereof;
FIG. 28 is a top plan view thereof;
FIG. 29 is a bottom plan view thereof;
FIG. 30 is a side view, with the opposite side view being a mirror image thereof;
FIG. 31 is a perspective view of a sixth embodiment;
FIG. 32 is a rear view thereof;
FIG. 33 is a right side view, the left side view being a mirror image thereof;
FIG. 34 is a top plan view thereof; and,
FIG. 35 is a bottom plan view.
